POSTAGE METER

Montague Moore, Burnaby, British Columbia,
Canada

Application August 11, 1937, Serial No. 158,527

16 Claims. (Cl. 101—91)

My invention relates to improvements in postage meters, the objects of which are to provide a postage meter which will be compact in form, of light weight and simple construction whereby its use can be extended to relatively small business institutions as well as larger ones. To provide means whereby the stacks of envelopes or cards of varying length may be put through the machine and have the stamp impressed on each in the proper place; to provide means whereby letters or cards however thin or soft will be properly carried through the machine and the postage applied be accurately recorded, and to provide simple means for changing the amount of postage to be impressed upon the letters and recorded as impressed.

The invention consists of a radially movable die mounted upon a rotating shaft, which die is provided with an interchangeable indicia representing postage values and means are provided for changing said indicia and causing the amount of the postage value to be recorded at each radial movement of the die, as will be more fully described in the following specification and shown in the accompanying drawings, in which:—

Fig. 1 is a plan view of the invention with the cover removed.

Fig. 2 is a longitudinal sectional view taken on the line 2—2 of Figure 1.

Fig. 3 is a detail view showing the rotating die and the gear train for changing the postage amount.

Fig. 4 is a detail sectional view taken on the line 4—4 of Figures 1 and 2.

Fig. 5 is a detail plan view showing the inking roll and its mounting.

Fig. 6 is an end view taken on the line 6—6 of Figure 2.

Fig. 7 is a sectional view taken on the line 7—7 of Figure 2.

Fig. 8 is a sectional view taken on the line 8—8 of Figure 1.

Fig. 9 is a sectional view showing the operating cam taken on the line 9—9 of Figure 1.

Fig. 10 is a plan view showing the feed shoes and dead rolls.

Fig. 11 is a plan view showing the feed rolls and entrance gatefingers.

In the drawings like characters of reference indicate corresponding parts in each figure.

The numeral 1 indicates a base having a bottom wall 2, side walls 3 and 4 and is partly enclosed by a bed plate 5 on which the letters are supported as they pass through the machine.

Supported upon the base is a housing 6 having

side walls 3 and 4 corresponding to those of the base, a front wall 7 and a rear wall 8. Suitably mounted alongside the base 1 is a motor 9 having a shaft 10 fitted with a worm 11 which meshes with a worm gear 12 upon a countershaft 13 extending longitudinally of the housing 6, see Figures 1 and 2. The countershaft is fitted with a pulley 14 for driving the feed rolls to be hereinafter described and also a pinion 15 which drives a main gear 16. Mounted longitudinally of the housing is a main shaft 17 which is journaled in bearings 18 and 19 and is fitted at its outer end with a turning knob 20 and at its inner end with a disc 21. Secured to the shaft 17 is a cam 22, which, with the main shaft 17, is frictionally driven by the main gear 16 bearing against the side of the cam under pressure of a friction spring spider 23 which is mounted on the inner face of a thrust collar 24 abutting the inner face of the bearing 18. The object of the frictional drive of the main shaft is to enable the shaft to be turned manually to a desired position to change the date die should such be used. The side walls of the housing are cut away at their lower edge to define a gap 25 through which the letters pass to be stamped.

Slidably mounted upon the disc 21 is a printing head 30 which is substantially in the form of an inverted T, as seen in Figure 2, the leg 31 of the T being apertured as at 32 to pass around the shaft 17 and adjacent its upper extremity it is provided with a guide 33 which extends through a radial slot 34 in the disc 21. The extremities of the head of the T forming the printing head 30 are suitably guided on the borders 35 of a gap 36 formed in the disc 21 so that the head of the T moves radially of the disc in which it is mounted. The printing head is retracted to its inner position as shown in Figures 2, 3 and 4, by one or more tension springs 36 which are anchored on one face of the disc 21.

The T printing head 30 is provided with an arcuate rim 37 which extends towards the main drive gear 16 and is adapted to be engaged by a press roll 38 to be hereinafter described, to move said plate outwardly from the axis of the main shaft 17. On the opposite side of the printing head 30, see Figure 3, is an arcuate flange or die 39 on which one or more stamps are embossed to imprint the letters passed through the machine. One of the stamps will indicate postage and the other, if used, will indicate the date of postage. These elements will be hereinafter referred to as the postage stamp, indicated by the

numeral 40 and the date stamp indicated by the numeral 41.

The date stamp 41 or a portion of it will necessarily need to be removable for changing the date 6 and will preferably be circular in form and provided with lugs 42 which will engage bayonet socket slots 43 formed in the die 39. Convenient means will be provided for the removal of the date stamp through a suitable opening in the 10 housing. Particular detail to this part of the structure is not deemed necessary as it forms no part of the invention.

The postage stamp 40 would be centrally apertured to permit the indicia representing value of 15 postage applied to project, this indicia is on the periphery of an indicia wheel 44 which is mounted upon a pin 45 carried by the head 30 and is fitted with a gear 46. The gear 46 is rotated from an idler 47 which is rotatably mounted on 20 a pin 48 mounted upon the disc 21. Rotatably mounted upon the inner end of the shaft 17 is a pinion 49 which is normally in mesh with the idler 47, and formed integrally with said pinion is one complementary member 50 of a dog clutch 25 51. The pinion 49 and the gear 46 are each provided with a suitable spring pawl or stop 52 which holds these elements frictionally against rotation, so that after an impression has been made by the stamps 40 and 41 and the head 30 30 recedes to its normal position the gears 47 and 46 will return to meshing position and the relative position of the teeth of the dog clutch member 50 to the numbers on the indicia wheel 44 will remain unchanged.

35 *Printing head operation.*—Mounted adjacent the rear wall 8 is a rock shaft 60 upon which is fixed an arm 61 provided at its outer end with a roller 62, which roller engages the underside of the cam 22 on the main drive shaft 17. An arm 63 40 extends from the rock shaft 60 which is engaged by a spring 64, see Figures 1 and 2, having a suitable anchorage adjacent the upper part of the housing for holding the roller 62 in constant engagement with the cam 22. Secured upon the 45 rock shaft 60 intermediate its length is a slide arm 65, shown in detail in Figure 4. This slide arm guides a vertically movable slide 66 which is here shown at its lowermost position and is returned to said position by a light spring 67. Projecting 50 inwardly from the slide 66 is a pawl 68 which is provided with a spring 69 to normally hold it at right angles to the slide 66. Freely mounted upon the rock shaft is a bell crank 70 which is provided with a stop 71 to limit its upward movement and 55 a spring 72 to raise it to its normal or inoperative position. The bell crank has legs 73 and 74, and at the free end of the leg 73 the roller 38 is mounted. The upper leg 74 of the bell crank 70 is provided at its free end with a throat 75 in which the 60 pawl 68 is received when the slide 66 is raised and the slide arm 65 is rocked inwardly.

65 *Feed roll assembly.*—A series of feed rolls 76, 77 and 78 are rotatably mounted within the base 1 on shafts 79, 80 and 81, which rollers are projected slightly above the bed plate 5. The shaft 79 is mounted in spring supported bearings 82, see Figures 2 and 4. The shaft 79 is fitted with two pulleys 83 and 83a, the shaft 80 is fitted with pulleys 84 and 84a, and the shaft 81 is fitted with 70 a pulley 85. A belt 86 connects the pulley 14 on the countershaft 13 with the pulley 83. A belt 87 drives the pulley 84 from the pulley 83a and a belt 88 drives the pulley 85 from the pulley 84a. Above the feed roll 77 is a dead roll 89 which is 75 mounted to float in slotted bearings 90 so that it

may lift according to the thickness of the letters entering the machine. A gate 91 which is adapted to be adjusted vertically in any convenient way, is fitted in front of the dead roll 89 and is spaced above the bed plate to permit the lowermost of a 5 pile of letters to enter the gap 25 into the housing.

10 *Trip mechanism.*—Mounted parallel to the dead roll 89 is a shaft 94 which is set above the gap 25 so that letters may pass freely thereunder. Upon this shaft a plurality of shoes 95 are fitted which are connected together for simultaneous movement by a push rod 96. Each of the trip shoes 95 15 are set close to the face of one of the rolls 77 so as to drop when in non-operative position slightly below the periphery of the rolls, as shown in Figure 4, and to project their free ends 97 upwardly above the entering letter that they may be raised thereby. Extending upwardly from the rod 96 is a push rod 98 having at its base a telescopic sleeve 99 in which a light spring 100 is provided. The 20 elongation of the telescopic portion of the rod is limited by a pin 101 extending through a slot 102 in the sleeve 99. The upper end of push rod 96 is provided with a finger 103 extending above a step 104. The step 104 is adapted to underly the slide 25 66 so that as a letter passes under the trip shoes 95 the slide 66 is raised and the pawl 68 is brought into line for engagement with the throat 75 of the bell crank leg 74, so that when the slide arm 65 is rocked the pawl will rock the bell crank 70. 30

35 Mounted below the bed plate 5 between the feed rolls 76 and 77 is a rocking shaft 111 from which a plurality of spring fingers 112 extend, which fingers are provided at their outer ends with upturned stops 113. These stops are adapted to bear 40 towards the lower border of the gate 91 at all times when a letter is passing under the shoes 95 and are urged upwardly by a suitable counter-weight 114. The shaft 111 is provided with a horizontally disposed arm 115 which is adapted to be depressed by a corresponding arm 116 mounted upon the shaft 94, when the trailing end of a letter has passed beyond the shoes 95 the shoes will drop, the arm 116 will press down the arm 115 and lower the stops 113 that another letter may be drawn 45 beneath the gate 91.

50 *Inking device.*—On the front wall 7 of the housing is a vertical slide 121 in bearings 122, and at the upper end of the slide a forked member 123 is 55 rockingly mounted upon a transverse pin 124, a stop 125 on the slide prevents the forked member 123 from dropping below the horizontal position shown in Figure 5 and a light spring 126 is provided for urging it downwardly towards the horizontal position. Rotatingly mounted on a perforated hollow spindle 127 carried in the forked member 123 is an inking roller 128 covered with pervious material in the usual manner. The spindle 127 is fitted at one end with an upstanding funnel 129 which is disposed immediately below a 60 small feed tube 130 extending through the top wall of the housing. A spring 131 serves to raise the slide 121 and a dash pot 132 of any suitable type is connected to the slide to retard its return to raised position. Coupled to the bell crank 70 65 to operate therewith is an arm 133 which engages a lug 134 on the slide 121 to depress it and bring the inking roller 128 down into contact with the flange and the postage and date stamps immediately following the impressing of a letter. 70

75 *Postage setting mechanism.*—Projecting from the inside of the side wall 3 of the housing is a collar 141, see Figures 1 and 2, which is supported on a pair of horizontal supports 142, non-rotatably mounted in this collar is a bearing sleeve 143 75

having a flange 144 at its inner end which is provided with indents 145 corresponding to the value of postage to be impressed, such as 1, 2 or 5 cents as the case may be. Rotatably mounted 5 in the bearing sleeve 143 is a hollow shaft 146 which is urged endwise by a spring 147 towards the side wall 3. At the inner end of the shaft 146 is a half clutch member 148 which is aligned with and complementary to the half clutch member 50 and forms part of the clutch 51. On the rear side of the half clutch member 148 is a pin 149 which is adapted to engage any of the indents 145 when the hollow shaft 146 is in normal endwise position and hold it against rotation. 10 At the outer end of the shaft 146 a head 150 is fitted, which is provided with a single transverse slot 151 on its face, see detail view in Figure 6, at one end of which a feather key 152 is fitted. Co-acting with the head 150 is a boss 153 formed 15 upon the side wall 3. This boss is circular in form and is recessed as at 154 from the outside of the machine to define an internal flange 155, see Figure 7. The boss is provided across its inner end with a plurality of radial slots 156 corresponding to the indents 145 on the flange 144. When the hollow shaft is in normal endwise position the key 152 of the head 150 is seated in the outer end of one of the slots 156, hence the shaft is still held against rotation. The rotation of 20 the shaft 146 is effected by a key 157 having a head 158 provided with a pointer 159 reading upon a graduated scale 160 on the wall 3 of the casing, which scale represents postage values to be impressed on the letters. The key 157 is provided with a stem 161 which passes through the flange 155, the head 150 and into the hollow shaft 146, and is provided with a transverse wing 162, which when in normal position, as shown in Figures 1 and 2, lies within a pair of opposed radial 25 slots 156 of the flange 155 and the single transverse slot 151 of the head 150. When the key is in the position shown, the postage value setting mechanism is in fixed position, but when said key is moved into its innermost position the wing 162 30 presses the hollow shaft 146 endwise to release the pin 149 from its indent 145 and passes beyond the flange 155, so that the key can be turned and through said wing turn the shaft 146. As soon as the wing 162 is clear of the flange 155 the 35 clutch members 148 and 50 are in full engagement and any turn of the shaft 146 imparts a similar turn to the gear train 49, 47 and 46, thus changing the stamp value to be impressed on the letters 40 passing through the machine.

55 *Recording mechanism.*—Extending radially from the half clutch member 148 is an arm 163 having at its free end a substantially V-shaped trip release 164, see Figures 1, 2 and 8, and directly coupled through a sleeve 165 secured to the 60 inker arm 133 is an arm 166 provided at its free end with a trip set 167, which arm will swing to move its trip set each time a letter is entered for postage impression. Extending from the disc 21 is a lug 168 upon which a rocker 169 is mounted 65 on an axis radial to the disc. The rocker is resiliently retained in either of its operating positions, as indicated in full and dotted line in Figure 1, by a throw over spring 170. To one side of the rocker is a dog 171 which is adapted to engage a stop 172 on the face of a half gear 173, on the outer face of the rocker 169 is a roller 174 which is adapted to strike the trip set 167 and on the inner face aligned with the roller 174 is a roller 175, see Figure 2, which is adapted to strike 70 the trip release 164 and move the rocker away 75

from the half gear 173. The half gear 173 is freely rotatable upon the sleeve 143 and is resiliently held against movement in a clockwise direction, as seen in Figure 8, by a spring 176 secured at one end to the hub of the gear and anchored at the other to a pin 177 extending from the bearing support 142. Mounted on the housing 6 is a counter 178 of any suitable type for recording the total amount of postage applied. This counter is driven by a free wheel gear 179 which operates the counter only when rotated in one direction, the gear is driven to operate the counter through an idler 180 which is in constant mesh with the half gear 173.

The operation of the machine is as follows:— 15 The motor when running imparts rotation to the shaft 17 and its disc 21 and also the feed rolls 76, 77 and 78. Letters are then placed into a suitable magazine 181 partly shown in Figure 10, the lowermost letter will be drawn by contact with the feed roll 78 under the gate 91, as the letter enters the bight between the feed roll 77 and the dead roll 89 it engages the shoes 95 and raises them and imparts an upward thrust to the push rod 98, which lifts the slide 66 and disposes its 20 pawl 68 in line with the throat 75 of the upper leg 74 of the bell crank 70. By the time that the forward end of the letter is passing over the feed roll 76 the cam 22 will be in such position as to rock the shaft 60 and since the pawl 68 is then 25 in line with the throat 75 the leg 73 of the bell crank will be lowered so that its press roll 38 will bear downwardly upon the arcuate rim 37 and move the printing head 30 radially so that postage and date stamps 40 and 41 respectively are 30 projected to the periphery of the disc 21 to impress postage and date upon the letter as it passes thereunder. Simultaneously with this movement the arm 133, coupled to the bell crank 70, is moved downwardly, drawing down the vertical slide 121 to the limit of its stroke, when the inking roller 128 will be in contact with the disc 21 and its forked member 123 will be raised at its free end since the slide travel is greater than that of the inking roller. By the time that the disc 21 has 35 turned to dispose the stamps 40 and 41 adjacent the inking roller 128 the stamps will have receded below the periphery of the disc to their normal position, but the spring 126 on the pivot pin 124 of the forked member 123 will swing said forked 40 member downwardly to bring the inking roller into contact with the stamps to re-ink them. The dash pot 132 will be adjusted so as to prevent the slide from rising beyond a predetermined 45 point until the re-inking has been completed, when its retarding action will be overcome and the inking roller and its slide 121 will be returned 50 by the spring 131 to normal position as shown in Figure 4.

Assuming the length of the letter passing 60 through the machine to be longer than the periphery of the disc 21 it will not have passed beyond the shoes 95, consequently the slide 66 which has been thrust down to the position shown in dotted line in Figure 4 will not be able 65 to return to its position upon the step 104 of the push rod 96 and will not in consequence be able to effect the printing of the letter a second time. The dropping of the slide 66 will be effected by the spring 69 as soon as the strain is relieved 70 between the pawl 68 and the throat 75 and the lower extremity of said slide is offset from the step 104. When the end of the slide 66 is overlapping the step as shown in dotted line, the roller 62 will be held out of contact with the non- 75

- operating part of the cam 22. As soon as the trailing end of the letter permits the shoes to drop the arm 116 will press down the arm 115 and lower the fingers 112 and their stops 113, so that another letter may be drawn into the machine. As the shoes drop the step 104 of the push rod 98 will return to normal and the slide 66 and its slide arm 65 will return to normal vertical position as shown in full line in Figure 4.
5. If a letter passing through the machine is relatively thick the spring 100 in the telescopic sleeve 99 will be compressed.
- By providing the shoes 95 with upturned free ends 97 which intersect the periphery of the feed rolls 77 tangentially and disposing said shoes in close proximity to the face of each roll thin card or paper will in passing lift said shoes without difficulty or without damage to the paper.
- Assuming the machine to have been set to print 2 cents postage the arm 163 on the half clutch member 148 set in a corresponding position as shown in Figure 2. The arm 166 will have been moved as the rock shaft 60 is rocked to cause the printing of the letter, which will dispose the trip set 167 in the path of the roller 174 on the rocker 169, the disc on rotating will cause the roller to engage the trip set and move the rocker over to the left, see Figure 1, when its dog 171 will come into the path of the stop 172 on the half gear 173. When the dog and stop meet, the half gear will be driven around until the roller 174 strikes the trip release 164 and breaks the driving train, when the spring 176 will return the half gear 173 to its position of rest.
20. During the driving of the half gear from the disc 21 the postage amount set will be added to the previous total of the counter 178.
- When the disc 21 is rotating without printing, the trip set 167 will be retracted from the path 40 of the roller 174, consequently no drive will be communicated from the disc 21 to the half gear and the counter will remain inoperative.
- To change the postage amount, the key 157 is pressed inwardly to release the wing 162 from its slots 156 and to engage the clutch 51, it is then turned to the desired amount, which rotates the gears 49, 47 and 46, thus disposing the desired postage value in printing position in the postage stamp 40.
50. What I claim as my invention is:
1. A postage meter comprising a bed plate, means for feeding letters across the bed plate, a housing enclosing a driven shaft, a printing die mounted about the shaft for movement radially thereof, a swinging arm for moving the die into printing position, normally disconnected cooperating elements adapted to be actuated by the shaft for operating the swinging arms to move the die radially outwards to imprint a letter, a shoe adapted to be raised by a letter entering the housing for connecting the cooperating elements to the swinging arm, and means for returning the printed die radially inward to normal position after the letter has been printed.
  55. 2. A postage meter comprising a bed plate, means for feeding letters across the bed plate, a housing enclosing a driven shaft, a printing die mounted about the shaft for movement radially thereof, normally disconnected cooperating elements adapted to be driven by the shaft for moving the printing die radially outward to imprint a letter, a shoe adapted to be raised by a letter entering the housing for connecting the cooperating elements to move the die radially outward, means for returning the printing die radially in-
  - ward to normal position after the letter has been imprinted, and means for disrupting the connection between the cooperating elements subsequent to the return of the die radially inwards and to prevent further connection between said elements while the shoe is held in raised position.
  60. 3. In a postage meter, a bed plate, a feed roller, a disc upon a shaft parallel to the feed roll, means for imparting continuous rotation to the disc, a printing head slidably mounted upon the disc, a bell crank rockable parallel to the face of the disc for moving the printing head into printing position, a postage stamp on the printing head, means as a letter is fed between the disc and the feed roll for rocking the bell crank to 15 dispose the postage stamp into printing position.
  65. 4. In a postage meter, a bed plate, a feed roller, a disc upon a shaft parallel to the feed roll, means for imparting continuous rotation to the disc, a printing head slidably mounted upon the disc, an arcuate rim on the periphery of the printing head, a postage stamp upon the printing head, a cam upon the shaft rotatable with the disc, said cam being mounted upon the same axis as the disc, and means associated with the arcuate rim and the cam for moving the printing head radially of the disc to dispose the postage stamp into printing position as a letter enters 20 between said disc and feed roll.
  70. 5. In a postage meter, a bed plate, a feed roller, a disc upon a shaft parallel to the feed roll, means for imparting continuous rotation to the disc, a printing head slidably mounted upon the disc, an arcuate rim on the periphery of the printing head, a postage stamp upon the printing head, a cam upon the shaft rotatable with the disc, a rock shaft, an arm upon the rock shaft adapted to be moved by the rock shaft, a bell crank freely movable upon the rock shaft having one leg adapted to move the printing head 40 radially of the disc to dispose the postage stamp into printing position, and means adapted on the entrance of a letter to the postage meter to engage the second leg of the bell crank to rock it and move the printing head.
  75. 6. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, and means on the slide 45 adapted when said slide is raised to engage the second leg of the bell crank to rock it.
  80. 7. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 50 adapted when said slide is raised to engage the second leg of the bell crank to rock it.
  85. 8. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 55 adapted when said slide is raised to engage the second leg of the bell crank to rock it.
  90. 9. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 60 adapted when said slide is raised to engage the second leg of the bell crank to rock it.
  95. 10. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 65 adapted when said slide is raised to engage the second leg of the bell crank to rock it.
  100. 11. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 70 adapted when said slide is raised to engage the second leg of the bell crank to rock it.
  105. 12. In a postage meter having a driven shaft, a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, one leg of the bell crank being adapted to engage the printing head to extend the postage stamp to the periphery of the disc, means on the slide 75 adapted when said slide is raised to engage the second leg of the bell crank to rock it.

adapted when said slide is raised to engage the second leg of the bell crank to rock it, and means for returning the bell crank to normal position.

8. In a postage meter having a driven shaft, 5 a disc and a cam upon the shaft, a printing head slidably mounted upon the disc, said printing head having a postage stamp adapted on the moving of the head in one direction to extend to the periphery of the disc, a rock shaft parallel to the driven shaft, an arm secured to the rock shaft adapted to be moved in one direction by the cam, a slide arm carried by the rock shaft, a bell crank, a slide within the slide arm adapted to be raised as a letter enters the postage meter, 10 one leg of the bell crank being adapted to engage the printing head to extend the postage stamp to the periphery of the disc, means on the slide adapted when said slide is raised to engage the second leg of the bell crank to rock it, and means 15 for lowering the slide after the rock shaft has been rocked to operate the bell crank.

9. In a postage meter, a rotary printing head comprising a disc, a T-shaped printing head 20 slidably mounted upon the disc, the head of the T being provided with a postage stamp and an arcuate rim disposed towards the periphery of the disc, means for resiliently maintaining the postage stamp below the periphery of the disc, and means actuated from a moving part of the 25 meter for intersecting the path of the arcuate rim to move the postage stamp towards the periphery of the disc, said means being actuated in response to the movement of a letter towards the disc.

30 10. In a postage meter, a driven shaft, a rotatable printing head upon the shaft mounted for radial movement toward and away from the shaft, a postage stamp upon the printing head, said postage stamp including a wheel bearing numbers indicative of postage values, and means aligned with the shaft and accessible exteriorly 35 of the meter for changing the postal value in the postage stamp.

40 11. In a postage meter, a driven shaft, a rotatable printing head upon the shaft mounted for radial movement toward and away from the shaft, a postage stamp upon the printing head, said postage stamp including a wheel bearing numbers indicative of postage values, and means aligned with the shaft and accessible exteriorly 45 of the meter for changing the postage value in the postage stamp, said means being operable with the driven shaft at any position of rotation of said shaft.

50 12. In a postage meter, a driven shaft, a disc upon the shaft, a radially movable printing head bearing a postage stamp adjacent the periphery of the disc, means for moving the printing head 55 radially outward into printing position, a rotary

member mounted on the printing head and bearing numbers representative of postal value co-operating with the postage stamp, means rotatable about the axis of the disc for turning the rotary member to change the postal value of the 5 postage stamp.

13. In a postage meter having a driven shaft, a printing head mounted for rotation with the shaft and for movement radially thereof, a rock shaft parallel to the driven shaft, said rock shaft having means for engaging the printing head to move it radially outward, a postage stamp on the printing head adapted to impress a letter, a feed roll, means operable in response to the passing of a letter over said feed roll for rocking 10 the rock shaft to urge the printing head and its postage stamp radially outward from the shaft, said means including a shoe having an upturned forward extremity, said shoe being disposed to project its lowermost portion below the periphery 15 of the feed roll whereby a letter passing between said shoe and the feed roll will raise the shoe above the periphery of the feed roll.

14. In a postage meter having a disc, a printing head radially movable upon the disc and normally retracted within its periphery, an inking roll normally out of contact with the disc and the printing head and means operable in response to the entrance of each letter to the meter for moving the inking roller into contact with the 25 periphery of the disc and subsequently with the 30 printing head.

15. In a postage meter having a rotating disc, a printing head movable radially of the disc, an inking roll normally at rest and out of contact 35 with the printing head, and means operable in response to the entrance of each letter to the meter for moving the inking roll into contact with the periphery of the disc whereby it is rotated up to the peripheral speed of the printing 40 head and for subsequently moving said inking roll into contact with said printing head.

16. In a postage meter, a bed plate, a feed roller, a disc upon a shaft parallel to the feed roll, means for imparting continuous rotation to the disc, a printing head slidably mounted upon the disc, an arcuate rim on the periphery of the printing head, a postage stamp upon the printing head, a bell crank adapted to engage the arcuate rim, a cam upon the shaft rotatable with the disc, said cam being mounted upon the same axis as the disc, and a rock shaft parallel to the disc shaft having an arm for engaging the cam, and means for engaging the bell crank to move the printing head radially of the disc to dispose 45 the postage stamp into printing position as a 50 letter enters between said disc and feed roll.

MONTAGUE MOORE.
